X R 9 11,655

No. 11633:

Feb. 17, 1880.

UNITED STATES PATENT OFFICE.

WILLIAM B. DURGIN, OF CONCORD, NEW HAMPSHIRE.

DESIGN FOR SPOON AND FORK HANDLES.

SPECIFICATION forming part of Design No. 11,655, dated February 17, 1880.

Application filed December 20, 1879. Term of patent 3½ years.

To all whom it may concern:

Be it known that I, W.M. B. DURGIN, of Concord, in the county of Merrimack and State of New Hampshire, have originated and designed a Pattern for the Handles of Table-ware, such as spoons and forks, of which the following description, in connection with the accompanying photographic illustration, is a specification.

10 The photograph shows the handle, the subject of this design, in three different sizes, both at front and rear, the said handle in some of the figures being employed with spoon-bowls, and in others with fork-tines.

15 Referring to the face or main side of the handle, it will be seen that it has about its edge a bead, *a*, which, at the large end of the handle, terminates in a crook, *b*, which falls just within a chevron, *c*, extended across the

20 rounded end of an oblong shield, *d*, the small pointed end of which is terminated by a shell-like ornament, *e*.

The center of the chevron is herein shown as composed of bars, but its edge resembles 25 a row of beads, the beads across the shield showing prominently.

The angle or point of the chevron is further ornamented with a pendant, *f*, extended out upon the shield.

30 Below the shell *e* is an ornamental figure, *g*, which is much like a *fleur-de-lis*.

Within the bead *a*, and about the shield and

the ornaments *e* and *g*, the face of the handle is wrought or traced, as at *h*, to resemble what is denominated "Swiss scroll-work."

35

The rear side of the handle is shown as provided with a bead, *i*, about its edge.

The new design for the rear of the handle consists of the calla-lily *k* and fern-like leaves *l*, held in a ring, *m*.

40

I claim—

1. The design for a handle for table-ware, composed of a shield, *d*, and a chevron, *c*, breaking in upon the shield, as shown.

2. The shield *d* and the shell-like ornament 45 *e* at its narrow end.

3. The shield, shell-like ornament *e*, ornament *g*, and the Swiss scroll-work, forming a background for the other parts herein named, and extending down into the shank of the 50 handle, as shown.

4. The shield with the chevron having a beaded edge and the crooked portions *b*, terminated within the chevron, as shown.

5. The design for the back of a handle, 55 composed of the calla-lily *k*, fern-like ornament *l*, and encircling-ring *m*, as shown.

In testimony whereof I have signed my name to this specification in the presence of two subscribing witnesses.

WILLIAM B. DURGIN.

Witnesses:

GEO. F. DURGIN,
F. W. SMITH.
